UNITED STATES PATENT OFFICE.

JOHN F. OHMER, OF DAYTON, OHIO, ASSIGNOR TO OHMER FARE REGISTER COMPANY, OF ROCHESTER, NEW YORK.

EXTERIOR OPERATING MECHANISM.

No. 911,517.

Specification of Letters Patent.

Patented Feb. 2, 1909.

Application filed August 6, 1907. Serial No. 837,289.

To all whom it may concern:

Be it known that I, JOHN F. OHMER, citizen of the United States, residing at Dayton, in the county of Montgomery and State of Ohio, have invented certain new and useful Improvements in Exterior Operating Mechanism; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to new and useful improvements in exterior operating devices through which mechanism of fare registers are actuated from different points of a car in which the registering machine is located.

More specifically speaking, the invention comprise an oscillatable member pivotal at a suitable point and adapted to be connected with pull-ropes or flexible connections extending in opposite directions and having a connection with the mechanism of the register or machine. The oscillating member is actuated a corresponding extent in either direction by the pull ropes so that the same extent of movement is imparted to the mechanism of the registering machine whether one or the other of the pull-ropes is drawn upon to actuate the oscillating member.

Preceding a detail description of the invention, reference is made to the accompanying drawings, of which—

Figure 1, is a front elevation of a registering machine having my improved appliance connected with the mechanism thereof. Fig. 2, is a detail view of the appliance detached from the registering machine. Figs. 3 and 4, illustrate modifications of the appliance as shown in Figs. 1 and 2.

In a detail description of the invention, similar reference characters indicate corresponding parts.

The device as shown in Figs. 1 and 2, comprises a triple-arm lever having three extensions or arms 4—5 and 6 radiating from a hub which is pivotally supported upon a pin 7 on bracket 8, said bracket being supported upon a wall 9 forming the usual partition which separates the interior of a car into two compartments. It will be observed that the hub of the triple-arm lever

is elongated in order that one of the arms, to-wit—arm 5, may be out of alinement with the arms 4 and 6 by extending from the hub at a point on one side of the other arms. It is important to have one of the arms so placed out of alinement with the other arms for the reason that such arm in the operations of the lever must move past one of the connecting rods in the operations of the lever. The pivot pin 7 lies at right angles to the bracket 8 in order that the oscillating member may be moved freely on its pivot. One arm of said oscillating member, to-wit—arm 5, has loosely connected thereto a link or rod 3, the other end of which is linked to the upper end of a bell-crank lever 2 which has its fulcrum in the rear of the register casing 1.

The mechanism of the registering machine which co-operates with the bell-crank lever, is illustrated in numerous of my prior patents, and it is only necessary herein to show the connection between the oscillating member comprising the present invention, and the bell-crank lever which is actuated thereby to impart movement to the register devices. The other two arms of the oscillating member are connected respectively, to ropes or pull-rods 11 and 12 by means of hooks 13 which are connected to eyes 14 formed in the ends of said arms. These rope or rod connections 11 and 12 extend in opposite directions on the interior of the car and on either side of the partition wall 9, one of said members passing through an aperture 10 in said partition. It will be understood that these rods or rope connections 11 and 12 are supported at suitable points on the interior of the car by means of a suitable number of brackets which provide a support and guide for the operation of the said ropes or rods. It will be understood that the oscillating member may be actuated in either of the two directions by pulling upon either of the ropes or operating connections, and that the movement thus imparted to the oscillating member will be transmitted to the bell-crank 2 in the rear of the register casing to actuate the mechanism of the machine.

The modification shown in Figs. 3 and 4, comprises a segment of a plate or disk 15 which is mounted upon the same pivot 7 and bracket 8; this segment of a disk has the three points of connection with the ropes or operating members 11 and 12 and the coup-

ling link 3, but instead of forming the eyes 14 as in the triple-arm lever, the connections are made between the hooks 13 and the segmental plate by means of staples 16 secured to the said plate or disk.

It will be observed that in the construction shown in Fig. 3, the link or rod 3 is pivoted to the plate 15 on one side thereof while the rods 11 and 12 are pivoted on the other side, therefore, the link 3 will not be interfered with as it will be out of alinement with the rods 11 and 12 in the operations of the plate 15. In both cases, the connections between the ropes or operating members 12—11 and 3 are loose in order that the parts 11 and 12 may through a reciprocating movement impart the proper oscillating movement to the oscillating member and the proper reciprocating movement to the connecting link 3.

Having described my invention, I claim:

1. A pivotal oscillating member for fare register actuating mechanism, comprising an oscillating member with operating connections extending from pivots on opposite sides of the axis of the oscillating member and affording means through which said oscillating member is reciprocated, in combina-

tion with an operating connection extending from said oscillating member and through which movement is transmitted from said oscillating member, the pivotal connection between the last-named operating connection and the oscillating member being out of alinement with the pivots between the first two operating connections and the oscillating member, substantially as specified.

2. In a device of the character specified, an oscillating member comprising a triple arm lever, said arms extending from an elongated hub and one of said arms being out of alinement with the others, operating connections extending from the two alined arms of said lever and by means of which the lever is actuated from distant points, and a movement-transmission connection extending from the arm of the lever which is out of alinement with the other arms, substantially as specified.

In testimony whereof I affix my signature, in presence of two witnesses.

JOHN F. OHMER.
